UNITED STATES PATENT OFFICE

2,682,079

APPARATUS FOR FORMING MINERAL WOOL

Charles D. Richardson, Anna, Ill., assignor to
Charles Richardson Corporation, Muncie, Ind.Original application July 19, 1951, Serial No.
237,508. Divided and this application March
26, 1952, Serial No. 278,679

2 Claims. (Cl. 18—2.5)

1

This invention relates to the conversion of molten slag into mineral wool and is similar in some respects to the invention disclosed in my prior U. S. application, Serial No. 215,463, filed March 14, 1951, and is a division of my copending application filed July 19, 1951, Serial No. 237,508. As in this prior application, the term "mineral wool" is used generally to cover slag, rock, glass, or similar materials which have been melted to form a molten slag and then fiberized.

In the above-identified application, Serial No. 215,463, an apparatus is disclosed which disintegrates a stream of molten slag by means of a peripherally channeled beater wheel. This wheel discharges a spray of the disintegrated slag in substantially a tangential direction, and the spray is fiberized by subjecting it to a high velocity enveloping jet of steam or hot air. While this apparatus is unusually efficient for rapidly producing an excellent grade of mineral wool, the present invention is designed to provide an improved apparatus and method capable of producing even greater tonnage per hour without in any manner impairing the quality of the product.

In carrying out the above end, a further object is to provide a high speed rotary cylinder into which the molten slag is fed for disintegration prior to fiberizing, said rotary cylinder having greater capacity than a beater wheel for disintegrating the molten slag and discharging a spray thereof.

Another object of the invention is to associate the slag-disintegrating cylinder in a novel manner with means for directing a high velocity jet of steam or hot air around and in contact with the spray of disintegrated slag issuing from said cylinder. This jet not only effectively fiberizes the spray, but confines the latter against being centrifugally thrown to any hazardous extent.

Yet another object is to rotatably mount the slag-disintegrating cylinder in a novel manner which permits it to be quickly and easily removed and allows another cylinder to be substituted with equal dispatch, whenever required.

A still further object is to provide an unusually simple yet highly efficient apparatus which may be expeditiously manufactured and profitably marketed at a reasonable price.

With the foregoing and other objects in view that will become apparent as the nature of the invention is better understood, the same consists in the novel subject matter hereinafter described and claimed, and shown in the accompanying drawings.

In the drawings:

Figure 1 is a side elevation, partly broken away and in section, showing the improved apparatus, Figure 2 is a front elevation, and

2

Figure 3 is a fragmentary vertical sectional view on line 3—3 of Figure 2.

A preferred form of construction has been shown and while this construction will be rather specifically described, it is to be understood that variations may be made within the scope of the invention as claimed.

A slag melting furnace is indicated at 5, and may be of any suitable form. It may be considered as of cupola type and provided with an adjustable discharge spout 6 for a stream of molten slag 7.

A rotary power-driven slag-disintegrating cylinder 8 is positioned to receive the slag stream 15. This cylinder centrifugally converts the molten slag into minute partially fiberized fluid particles which issue from the front end of said cylinder in the form of a sleeve-like spray 9. A circular steam or hot air nozzle 10 surrounds the front end of the cylinder 8 and forwardly projects a sleeve-like high velocity fiberizing jet 11 around the spray 9, thereby confining the latter against being centrifugally thrown to a hazardous extent. The jet 11 enveloping the sleeve-like spray 9, strikes and accelerates this spray and completes conversion of the latter into fibres, which fibres enter a chamber 12. This chamber is provided with a bottom in the form of a conveyor 13 upon which the fibres, felt or mat 20 and by which they are carried from the chamber for manufacture into bats or other mineral wool products.

The cylinder 8, a driving motor 14 for said cylinder, and the nozzle 10, are mounted on a stand 15. This stand includes a top plate 16 from which two front posts 17 and two rear posts 17^a project upwardly, said posts having bearings 18 and 18^a for the trunnions 19 of two lower rollers 20 which rotatably support the cylinder 8, said cylinder having peripheral flanges 21 at the ends of said rollers 20 to hold the cylinder against endwise movement. Front and rear links 22 and 22^a are pivotally supported by the trunnions 19 and extend upwardly therefrom at the sides of the cylinder 8. The upper ends of these links are provided with bearings 23 and 23^a for the trunnions 24 of two upper rollers 25. The upper ends of the two front links 22 are connected by a tension spring 26, and a corresponding spring 26^a connects the upper ends of the two rear links 22^a. These springs hold the rollers 25 inwardly against the cylinder 8, said rollers 25 therefore coating with the lower rollers 20 in mounting the cylinder for smooth rotation. The springs 26 and 26^a, however, are detachably connected at one end as indicated at 27 in Figure 2 and when here detached, they allow the links 22 and 22^a to outwardly swing.

Thus, the upper rollers 25 move away from the cylinder 8, leaving the latter free to be lifted out and replaced with another. After the replacement, the links 22 and 22^a are again swung inwardly and the springs 26 and 26^a are again connected. The cylinder driving motor 14 is geared at 28 to one of the lower roller trunnions 19 and thus the cylinder driving means is not disturbed when changing cylinder.

The axes of the rollers 20 and 25 are forwardly declined somewhat to support the cylinder 8 in a forwardly declined position, thus feeding the molten slag forwardly in said cylinder while it is being disintegrated. The period of time during which the slag remains in the cylinder, determines the diameter of the fibres produced by the apparatus; and said period may be varied by varying the point at which the slag stream 7 is discharged into said cylinder. When discharged about as shown in Figure 1, the slag will remain in the cylinder for the maximum period. The period of slag dwell in the cylinder may be reduced by discharging the stream 7 farther toward the front end of the cylinder, and this may be effected by substituting a longer chute 6.

Both ends of the cylinder 8 are open and the rear end of said cylinder is preferably flanged inwardly at 29 to prevent any back throw of the molten slag. The flange may well be of frustoconical form and will thus forwardly direct any fluid slag particles which may be centrifugally thrown against it.

The circular nozzle 10 is pivotally mounted at 30 in a U-shaped yoke 31, said yoke being secured to the upper end of a standard 32. This standard is adjustably secured at 33 to a slide 34, said slide being mounted on a track bar 36 secured to the stand 15. A hand screw 35 and nut 37 are shown for forwardly and rearwardly adjusting the slide 34, thereby similarly adjusting the nozzle 10 to attain the most advantageous setting.

An adjusting rod 38 is pivoted at 39 to the nozzle 10 for pivotally adjusting this nozzle to the most effective position, and suitable means 40 is provided for adjustably connecting said rod 38 with the stand 15.

For conducting steam or hot air to the nozzle 10, a valved line 41 is provided, including a length of hose 42. This line connects with the nozzle and communicates with a continuous chamber 43 of the latter as in Figure 3. A continuous narrow slit 44 is provided from the chamber 43 to the front side of the nozzle to discharge the high velocity jet 11 of steam or hot air. For most slags, a radial width of about forty thousandths of an inch is sufficient for the slit 44.

An excellent fibre can be formed when using a cylinder 8 of 6" internal diameter and 10' long driven at 1,000 R. P. M. However, the invention is not restricted to any particular cylinder dimensions or speed of rotation. The rotating cylinder centrifugally disintegrates the molten slag into minute partly fiberized fluid particles which discharge forwardly from said cylinder in the form of the sleeve-like spray 9. This spray is confined, struck and accelerated by the high velocity, forwardly directed sleeve-like jet 11 of steam or hot air, and complete conversion of the spray to fibres is thus effected. These fibres enter the chamber 12 and felt or mat upon the conveyor 13 which carries them off for manufacture into bats or other mineral wool products.

Whenever it is necessary to remove one cylinder and substitute another, this may be quickly and

easily accomplished by disconnecting the springs 26-26^a and swinging the links 22-22^a and rollers 25 outwardly. The cylinder may then be lifted from the rollers 20, and the replacement 5 laid upon said rollers 20. The links 22-22^a and the rollers 25 are then returned to their normal positions and the springs 26-26^a are re-connected again, placing the apparatus in condition for use.

From the foregoing it will be seen that novel and advantageous provision has been made for attaining the desired ends, and while there is herein shown and described the preferred embodiment of the invention, it is nevertheless to be understood that minor changes may be made therein without departing from the spirit and scope of the invention as claimed.

I claim:

1. A mineral wool producing apparatus comprising a slag-receiving cylinder having an open front end for forwardly discharging a sleeve-like spray of disintegrated and partly fiberized slag, means rotatably mounting said cylinder, said mounting means comprising rollers spaced 25 around the periphery of said cylinder and contacting with the latter, and mounting means for said rollers, including means mounting some of said rollers for outward movement from said cylinder, detachably connected spring means 30 normally preventing said outward movement, means for driving said cylinder, and nozzle means associated with the front end of said cylinder for directing a fluid jet against said spray to further fiberize the same.
2. In a mineral wool producing apparatus, a support, two front laterally spaced posts rising from said support and having bearings at their upper ends, two rear posts rising from said support behind said front posts, said rear posts having bearings aligned with those of said front posts, two lower rollers between said front posts and said rear posts, said rollers having trunnions engaging the bearings of said front and rear posts, a slag disintegrating cylinder resting on said two lower rollers, two upper rollers engaging said cylinder and normally holding it upon said lower rollers, right and left links carrying said upper rollers, said links being pivotally mounted at their lower ends to allow outward movement of said upper rollers when said cylinder is to be removed, 45 detachably connected springs connecting said right and left links and normally preventing outward movement of said links, a circular fluid discharge nozzle surrounding the front end of said cylinder, a U-shaped yoke in which said nozzle is mounted for tilting adjustment, a standard carrying said yoke, slide means mounting said standard on said support for forward and rearward adjustment, means for normally holding said nozzle in adjusted position with respect to said yoke, and means for normally holding said slide means in adjusted position.
